UNITED STATES PATENT OFFICE.

JAMES KYNOCH, OF TORONTO, CANADA, ASSIGNOR TO CANADIAN GENERAL ELECTRIC COMPANY, LIMITED, OF TORONTO, CANADA, A CORPORATION.

FRICTIONAL GEARING.

SPECIFICATION forming part of Letters Patent No. 728,400, dated May 19, 1903.

Application filed August 4, 1902. Serial No. 118,379. (No model.)

To all whom it may concern:

Be it known that I, JAMES KYNOCH, electrical engineer, of the city of Toronto, in the county of York, in the Province of Ontario, 5 Canada, have invented certain new and useful Improvements in Frictional Gearing, of which the following is a specification.

My invention relates to improvements in an apparatus for operating and controlling 10 gates or opening bridges; and the object of the invention is to devise a simple and effective means whereby the inertia may be easily overcome and the gate or bridge readily started and swung open or closed and, in 15 long narrow bridges particularly, without the jerk or whipping action which is always incident to such a class of bridge; and it consists, essentially, of a suitable drum and driving-gear connected thereto and journaled in 20 a suitable frame, a friction-gear designed to coact with the drum and having on the end of the spindle thereof a gear-wheel, a suitable motor having a pinion on the end of the shaft thereof designed to be in constant mesh with 25 the gear-wheel, a suitable lever and shaft and link-joints connecting the shaft to the bearings of the friction-gear, such bearings being located on the end of rocking arms swung on a center on a line with the axis of the driving- 30 pinion, and a suitable brake-shoe for the drum, such brake-shoe being suspended from an arm on the shaft to which the lever is keyed and being designed to coact with the friction-gear, the parts being arranged and constructed 35 in detail as hereinafter more particularly explained.

Figure 1 is a perspective view of the preferred form of my apparatus. Fig. 2 is a vertical cross-section.

40 In the drawings like letters of reference indicate corresponding parts in each figure.

A is the bed-plate of my apparatus, which is made of such a form as to suit the requirements. The main portion of the bed-plate is 45 provided with the standards B B and the end portion with the standards C, upon which is suitably bolted the motor D, as indicated.

E is a friction-drum secured to a shaft F, which is journaled in suitable friction-bearings 50 at the lower portion of the standards

B B. The shaft F has secured at one end thereof a bevel gear-wheel f' , which meshes with the bevel gear-wheel f^2 , secured on the end of the shaft F', which is the shaft designed to drive the mechanism from which 55 the gate or bridge is operated.

G is the minor friction-drum, which is made of any suitable material and is secured on the counter-shaft g. The counter-shaft g is journaled at the ends in the sleeves g', which are 60 provided with arms g², as indicated.

H is a cross-shaft which is provided with arms h, which are connected by the links h' h' to the arms g².

H' is the operating-lever, which is secured 65 on the outer end of the shaft H.

I represents arms, one only of which is shown, through which the counter-shaft g extends, such arms being pivotally swung on studs or a spindle i, axially opposite the shaft 70 d of the motor.

d' is a spur-pinion secured on the ends of the shaft of the motor and meshing with the spur-wheel g³, secured on the end of the cross-shaft g. 75

J is an arm which is secured on the cross-shaft H, and J' is a brake-shoe connected to the arm J by the link j.

It will be seen from what I have hereinbefore described that the cross-shaft g is journaled in adjustable or hung bearings. 80

The operation of the apparatus is as follows: In order to cause the driving-shaft F' to rotate, the handle or lever H' is thrown in the direction indicated by arrow, thereby 85 throwing the friction-drum G against the friction-drum E. As the gear-wheel g³ meshes with the gear-pinion D', it will be seen that the motion of the shaft of the motor D will be communicated, through the friction-drum 90 G, to the friction-drum E, thence to the shaft F'. By throwing the handle or lever H' in the opposite direction to that indicated by arrow the friction-drum G is removed from contact with the friction-drum E, and there- 95 by the drive of the drum E, and consequently the shaft F, is thrown out, and by continuing the movement of the lever in the reverse direction the brake-shoe J' is thrown against the drum E, so as to retard the speed of ro- 100

tation or impetus of the drum and bring it to a stop, thereby stopping the rotation of the shaft F'. It will thus be seen that by the simple movement of the lever H' in either one 5 direction or the other the shaft F' may be driven, retarded, or stopped.

As the shaft g is journaled in the sleeves g' and the shaft is connected by the arm I to a spindle or stud axially on a line with the 10 center of the shaft of the motor D, it will be seen that the friction gear or drum G may be thrown into or out of gear with the drum E without disturbing the driving connection between the gear-wheel g³ and the gear-pinion 15 on the motor-shaft D, as such gear-wheel g³ will roll upon the gear-pinion D' on account of the aforesaid connection by the arm I, and therefore the driving gear will be always in mesh, which is an important desideratum in 20 an apparatus of this class, as danger of breakage of the gears is reduced to a minimum.

Another important advantage I obtain in the construction of my apparatus is that the brake cannot be thrown in except when the 25 driving-gear is thrown out, which also serves to prevent breakages.

What I claim as my invention is—

1. In an apparatus for operating and controlling gates or opening bridges, the combination with a frame, motor and driving-shaft 30 thereof and the friction-drum and driving mechanism operated from same, of a coacting drum adjustably held against the aforesaid drum supported independently of the 35 driving-shaft, a driving means between such adjustable drum and the motor-shaft and means for adjusting the aforesaid drum without disturbing the position of the driving means as and for the purpose specified.

40 2. In an apparatus for operating and controlling gates or opening bridges, the combination with the frame, motor and driving-shaft thereof and the friction-drum and shaft thereof supported in suitable bearings in the 45 frame, of a coacting drum and the shaft thereof, bearings for the shaft hung from the frame, a gear on the end of the shaft deriving movement from the gear on the motor-shaft, means for raising the coacting drum 50 from contact with the main drum and further means for holding the drum-shaft in a concentric relation to the motor-shaft as and for the purpose specified.

55 3. In an apparatus for operating and controlling gates or opening bridges, the combination with the frame, motor and driving-shaft thereof and the friction-drum and shaft thereof supported in suitable bearings in the frame, of a coacting drum and the shaft 60 thereof, bearings for the shaft hung from the frame, a gear on the end of the shaft deriving movement from the gear on the motor-shaft, means for raising the coacting drum 65 from contact with the main drum, an arm pivoted on a stud or spindle axially opposite the motor-shaft, said arm having an opening

through which the shaft of the coacting gear extends as and for the purpose specified.

4. In an apparatus for operating and controlling gates or opening bridges, the combination with the frame, motor and driving-shaft thereof and the friction-drum and shaft thereof supported in suitable bearings in the frame, of a coacting drum and the shaft thereof, bearings for the shaft hung from the frame, a gear-wheel on the end of the shaft, a gear-pinion on the end of the motor-shaft with which such gear meshes and means for holding the shaft in a concentric relation to the motor-shaft, so as to always hold the gear 70 75 80 in mesh as and for the purpose specified.

5. In an apparatus for operating and controlling gates or opening bridges, the combination with the frame, motor and driving-shaft thereof and the friction-drum and shaft thereof supported in suitable bearings in the frame, of a coacting drum and the shaft thereof, bearings for the shaft hung from the frame, a gear-wheel on the end of the shaft, a gear-pinion on the end of the motor-shaft 85 with which such gear meshes and an arm pivoted axially opposite the motor-shaft, said arm having an opening through which the shaft of the coacting gear extends as and for the purpose specified. 90 95

6. The combination with the frame, motor and driving-shaft thereof and the friction-drum and shaft thereof supported in suitable bearings in the frame, of a coacting drum and the shaft thereof, sleeve-bearings for the shaft provided with arms, a supporting-shaft 100 journaled in suitable bearings in the frame, arms on the shaft, links connecting such arms with the arms on the sleeve-bearings and a lever for turning the shaft and driving 105 means between the end of the coacting-drum shaft, and the end of the motor-shaft as and for the purpose specified.

7. The combination with the frame, motor and driving-shaft thereof and the friction-drum and shaft thereof supported in suitable 110 bearings in the frame, of a coacting drum and the shaft thereof, sleeve-bearings for the shaft provided with arms, a supporting-shaft journaled in suitable bearings in the frame, 115 arms on the shaft, links connecting such arms with the arms on the sleeve-bearings and a lever for turning the shaft, and a gear-wheel on the coacting-drum shaft and a gear-pinion on the end of the motor-shaft with which the 120 same meshes as and for the purpose specified.

8. The combination with the frame, motor and driving-shaft thereof and the friction-drum and shaft thereof supported in suitable 125 bearings in the frame, of a coacting drum and the shaft thereof, sleeve-bearings for the shaft provided with arms, a supporting-shaft journaled in suitable bearings in the frame, arms on the shaft, links connecting such arms with the arms on the sleeve-bearings, a lever 130 for turning the shaft, and a gear-wheel on the coacting-drum shaft and a gear-pinion on the

end of the motor-shaft with which the same meshes and an arm through which the coacting-drum shaft extends, such arm being pivoted on a line with the axial center of the 5 motor-shaft as and for the purpose specified.

9. The combination with the main drum and the coacting drum and driving means, of means for removing the coacting drum from contact with the main drum and means for 10 providing for a continuous connection between such coacting drum and the driving means consisting of the two gears one of which has movement about the axis of the other as and for the purpose specified.

15 10. The combination with the main drum and coacting drum and the bearing-sleeves and arms forming part of the same, of the cross-shaft, arms and links connecting them

with the arms on the sleeves, an arm extending from the opposite side of the cross-shaft, 20 a brake-shoe and link connecting it with the aforesaid arm and means for rocking the shaft as and for the purpose specified.

11. In combination, a main drum, a coacting drum and brake-shoe to act on the main 25 drum, a shaft, means for operating the said shaft and connections extending therefrom in opposite directions for moving the brake-shoe and coacting drum in opposite directions in relation to the main drum, substantially 30 as described.
